UNITED STATES PATENT OFFICE.

EZRA LOFTS, OF CAMBRIDGE, ENGLAND.

COOKING-RANGE.

SPECIFICATION forming part of Letters Patent No. 367,150, dated July 26, 1887.

Application filed May 28, 1886. Serial No. 203,557. (No model.) Patented in England May 7, 1884, No. 7,356.

To all whom it may concern:

Be it known that I, EZRA LOFTS, a subject of the Queen of England, residing at Cambridge, in England, have invented certain new and useful Improvements in Cooking Ranges or Stoves, (for which I have obtained a patent in England No. 7,356, dated May 7, 1884,) of which the following is a full, clear, and exact description.

Referring to the drawings, Figure 1 is an isometric view of a cooking range or stove embodying my improvements. Fig. 2 is a section thereof, taken on line $x-x$ of Fig. 3. Fig. 3 is a section taken on line $y-y$ of Fig. 2. Fig. 4 is a section taken on line $z-z$ of Fig. 2, and Fig. 5 is a section taken on line $1-1$ of Fig. 1.

The general principles upon which this stove is constructed are the same as those of the domestic and other fire-grates for which I have made application for patent, Serial No. 172,234.

The object of this invention is to provide a cooking range or stove which will more effectually consume the smoke than many of those at present in use, and at the same time increase the heating capacity of the apparatus.

The invention consists in certain features of construction and combination of parts, substantially as hereinafter fully described, and as set forth in the claims.

In the drawings, A indicates the grate for the reception of the fuel, open in front, the fuel being prevented from falling out by grate-bars a . Below the grate is the ash-pit, in which is fitted a drawer or pan, B, of greater length than the depth of the ash-pit, the part of the pan projecting in front of the grate being of a depth equal to the distance from the upper face of grate A to the bottom of the ash-pit, and said part is open at top to admit air freely under the grate, as shown in Figs. 1 and 3.

When but little fire is required, or when it is desired to cook with a wood fire, I employ an auxiliary-grate, A', provided with feet a' , and adapted to fit into the fuel-chamber and rest upon the grate A, as shown in Figs. 1 to 4.

C is a door hinged to the range above the upper front grate-bar a , to afford means to admit large volumes of air into the space S' below the top of the range when this is desirable.

D is a back plate arranged in rear of the grate A and constituting the back of the fuel-

space. The plate D is perforated or constructed in the form of a grate, with grate-bars d extending nearly to the upper edge thereof. The back plate is fitted in grooves formed in the side walls of the fire-space, which walls may be formed by one side of two boilers, E E', or by an intervening fire-brick lining, a^2 , as shown more plainly in Fig. 4.

The two boilers E E' are so arranged as to leave a clear space around the sides and bottom thereof, said boilers being supported from the bottom b of the range by means of suitable feet or stays, e, Fig. 2, and are connected together by cross-duct E^2 , that serves as a seat for the back of the combustion-chamber F, formed between the back plate, D, of the fuel-space and the oven O. This back of the combustion-chamber may be formed by the front vertical wall of the oven; but as the heat in the combustion-chamber is very intense, I prefer to employ as a back for the combustion-chamber a fire-brick back, G, said fire-brick being seated on the connecting-branch E^2 of the two boilers E E'.

The oven O is so arranged relatively to the top, bottom, and back walls and the rear end wall of the stove as to leave a clear space above and below the oven and a like space at the back and rear end thereof, as shown in Figs. 3 and 4.

The space at the rear end of the oven is divided into three flues, $c' c' c^2$, by partitions $p' p^2$, which partitions may extend clear down to the bottom b of the range, thus forming three flues, communicating with the spaces S and S' below and above the oven, respectively. The central flue, c , communicates with the draft-pipe P, and in the space S' above the oven is arranged a cross-partition, H, the central portion of which in front of flue c is provided with a multiplicity of vertical slots, h , and at opposite ends of said partition are openings h' , leading into flues $c' c^2$, adapted to be closed by dampers $I' I^2$, secured to a damper-rod, I, that has its bearings in the opposite side walls of the range, and carries on that side in which the oven-opening is formed a crank-handle, I^3 , for manipulating the dampers.

By means of the described arrangement the communication between the flues $c' c' c^2$ through space or chamber S' may be cut off or established, as desired. In rear of the slotted por-

tion of the partition H is arranged a sliding damper, H', also slotted, and having a sliding motion sufficiently great to cover and uncover the slots in the partition H when moved toward one or the other side by means of the handle H², that projects through and works in a slot, s, formed in the range-top. (See Fig. 1.)

As shown by Fig. 4, when the dampers I' I² and the sliding damper H' are closed the heat and products of combustion cannot pass directly from the grate into either of the flues c c' c², and to prevent such products of combustion from rising up through the space S² at the 15 back of the oven the top o of the latter may be extended over said space; or a portion of the said top of the oven may be extended over the space S², as shown at o', and a vertical partition, p³, may be provided and arranged so as 20 to close the remainder of the space, as shown in Fig. 4, and prevent the products of combustion from ascending through space S² into space S'.

The back D of the combustion-chamber extends, as shown in Fig. 3, some distance below the grate opposite the ash-pit back plate, p⁴, which latter and the back D and connection E² of the boilers E E' form a diving-flue, F', communicating with the combustion-chamber 30 and opening into a space formed by a bench or extension, K, of the lower portion of the range, which serves as a heat-radiating chamber. The products of combustion may therefore be conducted directly from the combustion-chamber F through the diving-flue F' or extension of the combustion chamber under the oven, and thence to flue c and the draft-pipe P. If it is desired to still further utilize the 35 heat of the products of combustion, their course may be diverted from that just described toward the front of the extension K by means of a sliding damper, L, constructed to form a transverse horizontal partition, said damper being provided with wings L', extending along the boilers E E' to the 40 opposite sides of the extension of the range, as more plainly shown in Fig. 5. The damper is of such length that when fully pushed in to cut off the direct communication between the combustion-chamber F and the 45 space S, formed between the bottom b of the range and the bottom of the boilers and oven, there will be an open space left between the outer edge of said damper and the front wall 50 of the extension K of the range, as shown in Fig. 5. This damper I have fully described and shown in my application for patent hereinbefore referred to, and do not desire to claim it broadly herein.

60 In practice I make the front wall of the extension K removable, so that when the damper L is removed the space S below the boilers and oven will be entirely free from obstructions for the removal of such solid products of combustion or ashes as are carried along by the draft, as well as the soot that may form therein. The damper L is provided with a handle, L²,

that projects through a slot formed in the front wall of the extension K, as shown in Fig. 1.

The top of the range is provided with suitable pot-holes, as usual, the parts that form these holes being removable, so that ready access may be had to the space S' above the oven back of the combustion-chamber and to the grates. The flues c c' are also provided 75 with openings closed by lids, so that access thereto may be had for the purpose of cleaning the same, a like opening closed by a lid, n, being formed above the space inclosed by the partition p³, so as to gain access to the space 80 S' between the oven and the back wall of the range.

By means of the described construction the draft may therefore be adjusted as follows: First, by moving the damper L out and closing the dampers I' and I² and the slide H' all the products of combustion will pass from the combustion-chamber F through diving-flue F' into space S below the bottom of the boilers and oven, and thence to flue c and to draft-pipe P; second, by opening the slide H' a portion of the products of combustion will follow the described course and another portion will pass directly through the space S' above the oven to flue c and the draft-pipe P; third, by 90 closing the slide H' and opening the dampers I' I² a portion of the products of combustion will pass through combustion-chamber F, flue F', space S to flue c and the draft-pipe P, and the other portion of said products of combustion will pass directly through space S' into diving-flues c c', and thence into space S, to flue c, and draft-pipe P; fourth, by moving the damper L in those I' I², and the slide H' being closed, all the products of combustion 100 will pass from combustion-chamber F and flue F' over damper L to front wall of extension K of the range, and thence under the damper into space S, to flue c, and the draft-pipe P; fifth, by moving the damper L in and opening 110 the slide H' the main draft will be directly through space S' to flue c, and by opening the dampers I' I² also the draft will be divided, a portion of the products of combustion passing direct to flue c through H', another portion 115 through flues c c' to S, thence to flue c, and a third portion through F' to front wall of extension K, and thence through S to flue c, and finally, by closing H', opening I' I², and pushing in the damper L, the draft will be nearly equally 120 divided in the direction of S' c c' S c and F' L S c.

It will be seen that the temperature of the range itself, as well as the temperature in the oven, may be variously regulated, and this is 125 a very important point in apparatus of this character.

There is another very important feature connected with my invention, in that cold air cannot possibly be admitted to the combustion-chamber F', and as all air admitted thereto must pass either directly through the back of the fuel-space or over the same said air reaches the combustion-chamber at a temperature best 130

suited to promote the combustion, thereby effecting a material saving in fuel.

When it is desired to utilize a portion of the heat for purposes of heating other rooms, the back G of the combustion-chamber may be removed and a water-back connected therewith and provided with suitable feed and circulating pipes, or said water-back may extend the full height occupied by the connection E' and the back G, and may be connected with the boilers E E', in which case the latter are provided with suitable feed and circulating pipes.

In most stoves and ranges as now constructed and provided with ovens the heat above the oven is much greater than below the same. This is not the case in the range above described, as means are provided for diverting the greatest heat either from the bottom or the top of the oven. In case it should become necessary to keep the top of the oven comparatively cool, the door C can be opened, together with the slide H', and the damper L moved outward, and it will be found that the air entering above the grate into space S' will be almost cold on reaching the slide H'. The greatest heat will then be at the bottom and side of the oven, as will be readily understood.

I do not desire to claim, broadly, in this application a grate having a perforated or slotted back, a combustion-chamber in rear thereof, a diving-flue communicating with the combustion-chamber, with a chamber or hearth extending forwardly of the grate and with the draft-flue and means whereby the products of combustion may be directed directly to the draft-flue or indirectly through the hearth, as described, these features constituting the subject-matter of an application for a patent of the United States filed July 21, 1885, Serial No. 172,234.

Having now particularly described my invention, what I claim is—

1. A cook-stove comprising an oven, a vertical flue at one end thereof communicating with the draft-pipe, a flue below the oven communicating with the end flue, a grate, a perforated or slotted grate-back, a combustion-chamber formed by and between the grate-back and the opposite end of the oven, and a diving-flue communicating with the combustion-chamber and the flue underneath the oven, substantially as and for the purpose specified.

2. A cook-stove comprising an oven, a vertical flue at one end thereof communicating with the draft-pipe, horizontal flues extending over the top and under the bottom of the stove and communicating with said vertical flue, a grate, a perforated or slotted grate-back, a combustion-chamber formed by and between said grate-back and the other end of the oven, a diving-flue communicating with the combustion chamber and the flue below the oven, and a damper in the flue above the oven to cut off the communication between said

flue and the vertical end flue, substantially as and for the purpose specified.

3. A cook-stove comprising an oven, a vertical flue at one end thereof communicating with the draft-pipe, horizontal flues above and below the oven communicating with said vertical flue, a grate, a perforated or slotted grate-back having a solid portion extending above the fuel-space with its upper edge on a line with the roof of the oven, a combustion-chamber formed by and between the grate-back and the opposite end of the oven, a diving-flue communicating with the combustion-chamber and the flue below the oven, and a damper in the flue above the oven to cut off communication between the said flue and the vertical end flue, substantially as and for the purpose specified.

4. A cook-stove comprising an oven, a vertical flue at one end thereof communicating with the draft-flue, horizontal flues above and underneath the oven, an open-front grate, a door in the front wall of the stove above the fuel-space of the grate and on a line with the upper horizontal flue, a perforated or slotted grate-back having a solid portion extending above the fuel-space with its upper edge in line with the roof of the oven, a combustion-chamber formed by and between the grate-back and the opposite end of the oven, a diving-flue communicating with the combustion-chamber and the flue underneath the oven, and a damper in the flue above the oven to cut off the communication between the same and the end vertical flue, substantially as and for the purpose specified.

5. A cook-stove comprising a grate, two vertical boilers forming the side walls thereof, and a horizontal connection between said boilers below and in rear of the grate, forming a seat for the lining, substantially as and for the purpose specified.

6. A cook-stove comprising a grate, two vertical boilers forming the side walls thereof, supported in the stove to leave a space below and around the other three sides of said boilers, and a horizontal connection between the boilers below the level of the grate, forming a seat for the lining, substantially as and for the purpose specified.

7. A cook-stove comprising an oven, a vertical flue at one end thereof communicating with the draft-pipe, horizontal flues at top and underneath the oven communicating with said vertical end flue, a flue extending over the back of the oven in communication with the flue underneath the oven, a grate, a perforated or slotted grate-back having a solid portion extending above the fuel-space with its upper edge on a level with the roof of the oven, a combustion-chamber formed by and between said grate-back and the front end wall of the oven, a diving-flue communicating with the combustion chamber and the flue below the oven, and a damper in the flue above the oven for cutting off the communication between the

same and the vertical end flue, substantially as and for the purpose specified.

8. A cook-stove comprising an oven arranged within the stove to leave a clear space between one of its end walls and between its roof, floor, and back wall and the corresponding walls of the stove, partitions dividing the vertical end space into three flues communicating, respectively, with the space above and below the oven, one of said flues also communicating with the draft-pipe, a partition isolating the space at the back of the oven from the space above the roof thereof, a set of dampers for cutting off the communication between said space above the oven and the three flues at the rear end thereof, a grate, a perforated or slotted grate-back, a combustion-chamber formed by and between said grate-back and the front end wall of the oven, and a diving-flue communicating with the combustion-chamber, and the space below the oven, substantially as and for the purpose specified.

9. A cook-stove comprising an oven, a space between the top and bottom thereof and the top and bottom of the stove, a vertical flue at one end of the oven communicating with said spaces and the draft-pipe, a grate, two vertical boilers forming the opposite side walls of the grate, a perforated or slotted grate-back, a combustion-chamber formed by and between said grate-back and the front end wall of the oven, a diving-flue communicating with the space below the bottom of the oven, a connection below the level of the grate for connecting the vertical boilers, the front wall of said connection forming one of the walls of the diving-flue and the top wall a seat for the lining of the combustion-chamber, and a damper interposed in the communication between the space above the oven and the rear vertical flue, substantially as and for the purpose specified.

10. A cook-stove comprising a grate, an ash-pit below the same, an oven in rear of the grate, a space between the top and bottom of the oven and its corresponding walls of the stove, a chambered hearth below the ash-pit communicating with the space below the oven and extending forward from the grate-back beyond the grate-front, a vertical flue at the rear end of the oven communicating with the spaces above and below the same and with the draft-pipe, a perforated or slotted grate-back, a combustion-chamber formed by and between said grate-back and the front end of the oven, a diving-flue communicating with the combustion-chamber and the chamber in the hearth, and a damper interposed in the com-

munication between the space above the oven and the end vertical flue, substantially as and for the purpose specified.

11. A cook-stove comprising a grate, an ash-pit below the same, an oven in rear of the grate, a space between the top and bottom of the oven and the corresponding walls of the stove, a vertical flue at the rear end of the oven communicating with said spaces and with the draft-pipe, a chambered hearth extending from the grate-back below the ash-pit, beyond the grate-front, and communicating with the space below the oven, a grate-back, a diving-flue formed by and between said grate-back and the front end wall of the oven and communicating with the chambered hearth, and a slide-plate constructed to divide the chamber of the hearth into two compartments, cut off the direct communication between the diving-flue in rear of the grate and the space below the oven, and conduct the products of combustion over said plate to the front of the hearth, thence under the same to said space below the oven, substantially as and for the purpose specified.

12. In a cook-stove, the combination, with the grate A and its back plate, D, of the boilers E E', their connection E², the oven O, arranged relatively to the grate, its back plate, the boilers and the walls of the stove to form the spaces or passages S S' S² F F', said boilers forming the opposite side walls of the grate, the partitions p' p² in the space formed between the rear wall of the oven and that of the stove, the dampers I' I², and the dampers H H', said parts being arranged for operation substantially as and for the purpose specified.

13. In a cook-stove provided with the chambered hearth K, the combination, with said hearth, the grate A, and the back plate, D, thereof, of the boilers E E', arranged to form the opposite side walls of the grate, the oven O, arranged relatively to the inclosing-walls 100 of the stove, the grate-back, and the boilers to form the spaces S S' S² F F', and the flues c' c², the dampers I' I², the damper H', and the slide L, the said parts being arranged and operating substantially as and for the purpose 105 specified.

In testimony whereof I have hereto set my hand in the presence of the two subscribing witnesses.

EZRA LOFTS.
